CLAIM

The ornamental design for a cabinet for an oxygen concentrator, as shown and described.

DESCRIPTION

FIG. 1 is a perspective view of a cabinet for an oxygen concentrator showing our new design;

FIG. 2 is a right side elevational view thereof;

FIG. 3 is a rear elevational view thereof;

FIG. 4 is a bottom plan view thereof;

FIG. 5 is an enlarged top plan view thereof;

FIG. 6 is a front elevational view thereof, shown in an open position;

FIG. 7 is a rear elevational view of an alternate embodiment of the design shown in FIG. 1; and,

FIG. 8 is an outside elevational view of FIG. 7, shown in an open position.
